UNITED STATES PATENT OFFICE

WILLIAM W. LASKER, OF BROOKLYN, NEW YORK, ASSIGNOR, BY MESNE ASSIGNMENTS,
TO REMINGTON RAND INC., OF NEW YORK, N. Y., A CORPORATION OF DELAWARE

ACCUMULATOR OPERATING MECHANISM

Application filed July 23, 1925. Serial No. 45,577.

The present invention relates generally to adding machines but more particularly to the accumulating mechanism operated by a sector such as employed in printing tabulators.

Some of the objects of the present invention are to provide an improved means for controlling the operation of an accumulating and total taking mechanism; to provide means for causing a positive meshing relation between the pinions of the accumulator mechanism and their sectors whereby an accurate rolling in of an accumulation or an accurate rolling out of a total is accomplished; to provide an accumulator mechanism having a measure of flexibility whereby abnormal strains may be relieved without damage; to provide means including a toggle mechanism in place of a rigid cam operated device for controlling accumulator pinions; and to provide other improvements as will hereinafter appear.

In the accompanying drawings, Fig. 1 represents a fragmental detail of a printing tabulator having an accumulator operating mechanism embodying one form of the present invention and showing the sector and accumulator pinion in disengaged position; and Fig. 2 represents the same with the parts moved to bring the accumulator pinion into engagement with the sector.

Referring to the drawings, those portions of a printing tabulator which are believed necessary to an understanding of the present invention are shown and consist of a type sector 10, an accumulator pinon 11, an accumulator link 12 and operating mechanism for the machine comprising a crank sector 13, mounted on the main actuating shaft 14 and arranged to engage a pivoted crank sector engaging lever 15. This lever 15 transmits motion to a link actuating lever 16 which carries at opposite ends the pins 17 and 18 for engagement respectively with the upper and lower recesses 20 and 21 of the accumulator link 12, depending upon whether the link 12 is in its raised or lowered operating position so that the link 12 is operated at the proper predetermined times in the operation of the machine. For shifting

the link 12 from one operating position to another according to requirements it is connected by a slot 22 and pin 23 to a motion transmitting link 24 which has its opposite end pivoted to a rock arm 25. A spring 26 is connected between the arm 25 and the link 12 to maintain the normal relation between the parts. The foregoing structure is fully described in Patent No. 1,388,271 and need not here be further explained except to mention that the accumulator link 12 as here shown is a two part flexible link instead of a rigid link as in the aforesaid patent and forms the subject matter of a pending patent application.

The accumulator pinion 11 is carried by a shaft 27 supported by an arm 28 mounted for swinging movement about a fixed pivot 30 in such a manner that movement of the arm 28 in one direction brings the pinion 11 to meshing relation with the rack 31 of the sector 10, and in the opposite direction brings the pinion 11 out of such meshing relation.

For the purpose of actuating the arm 28 to give the desired pinion action, a relatively short link 32 is pivoted at one end on the shaft 27 and at its other end is attached by a pivot pin 33 to an arm 34 which is pivoted on a pin 35 of rigid ears 36.

In order to transmit motion to the arm 34 it is connected by a pivot 37 to one end of the accumulator link 12 so that as the latter is moved in one direction or the other a corresponding rocking of the arm 34 takes place to shift the pinion as circumstances require. The link 32 and arm 34 as connected form a toggle structure operating in straightened position to hold the pinion 11 firmly in its meshing position, and when in broken position to remove the pinion from meshing position.

To accelerate the toggle change from position to position, a spring 38 is stretched between a pin 39, on the arm 34, and a pin 40 on a side extension 41 of the short link 32. This extension 41 extends at an angle to the link 32 so that when the toggle is straightened or broken the spring 38 is stretched and relieved as the fulcrum 33 crosses the spring, and hence a shifting of the toggle fulcrum

either to pinion meshing or unmeshing position brings the tension of the spring 38 into play to give a snap action as soon as the fulcrum passes to a side of it. Any tendency 5 of the toggle to collapse or move beyond prescribed limits is prevented by the provision of a stop pin 42 carried by a rigid arm 43 and entering an opening 44 in the arm 43. The opening 44 is so proportioned that when 10 the arm 34 reaches the necessary limit of its movement in either direction, the stop 42 will be engaged and prevent further movement.

In the operation of the machine the sector 15 10, when swinging to type setting position, is out of mesh with the pinion 11 and the latter and its operating parts are then in the position of Fig. 1 but before the return movement of the sector begins the pinion 20 11 is thrown into mesh with the sector to roll in an accumulation. This shifting of the pinion 11 takes place automatically and by the correct timing of the parts which move the accumulator link 12. The movement 25 of the accumulator link 12 is in the direction to straighten the toggle link 32 and arm 34 so that the spring 38 finally snaps the parts to the desired meshed relation. The unmeshing of the parts takes 30 place through movement of the accumulator link 12 in the opposite direction and the break in the toggle draws the pinion 11 to the position shown in Fig. 1. Where a total 35 is to be rolled out of the accumulator link 12 is moved to neutral position to permit the accumulator pinions to remain in mesh with the sectors during the forward stroke. If the accumulator is to remain clear, the link 12 will be lowered as usual to engage the 40 slot 21 with the pinion 18 to disengage the accumulator from the sectors before the return stroke is made.

It will now be apparent that an accumulator 45 control mechanism has been provided which is simple and effective to control the meshing and unmeshing of accumulator pinions with rack sectors for registering, accumulating and taking of totals. By the present invention cam operated controls heretofore employed have been dispensed with and consequently rigid non-giving action is avoided and the use of adjustable detents no longer necessary. The necessary adjustments required and accompanying the use of cams, 50 detents and latches have heretofore made skilled operation a very material factor in the use of machines of the character here under consideration and where through wear or strains, due to rigid positioning of the accumulator pinions, the proper meshing does not take place, the machine must remain idle 55 while repair and skilled readjustment are made. Disadvantages of this character are entirely obviated by the present means for meshing and unmeshing the accumulator pin-

ions and a flexibility of control obtained which functions automatically to take up and compensate for wear, to maintain adjustment, and to relieve abnormal strains.

While only a single form is shown in which this invention may be embodied, it is to be understood that the invention is not limited to any specific construction, but might be applied to various forms without departing from the spirit of the invention or the scope 75 of the appended claims.

Having thus described my invention, I claim:

1. In a device of the character stated, the combination of a rack sector, an accumulator pinion, means including a toggle structure for meshing and unmeshing said pinion with said rack sector, and means for accelerating the straightening and breaking of said toggle structure.
2. In a device of the character stated, the combination of a rack sector, an accumulator pinion, means including a toggle structure for meshing and unmeshing said pinion with said rack sector, and a spring between parts of said toggle and movable from one side of the toggle fulcrum to the other.
3. In a device of the character stated, the combination of a rack sector of a computing machine, an accumulator pinion, a pivoted arm carrying said pinion, a toggle between said arm and a fixed point adapted in its straightened position to limit the extent of meshing of the pinion with the rack sector, and operating mechanism for the machine including means for straightening and breaking said toggle at predetermined times in the operation of said mechanism whereby said pinion is caused to mesh and unmesh with said rack sector.
4. In a device of the character stated, the combination of a rack sector, an accumulator pinion, a pivoted arm carrying said pinion, an arm pivoted to a fixed point, a link connecting said arms and forming a toggle with said second arm, a spring connected at one end to said second arm, means on said link for attaching the other end of said spring and offset with respect to the fulcrum of said toggle, and means for straightening and breaking said toggle whereby said pinion is caused to mesh and unmesh with said rack sector.
5. In a device of the character stated, the combination of a rack sector, an accumulator pinion, means including a toggle for meshing and unmeshing said pinion with said rack sector, a spring connected between said toggle parts, to actuate the toggle toward either of its limits after it has moved past the center toward said limits, and means to limit the movement of said toggle in either direction.
6. In a device of the character stated, the combination of a rack sector, an accumulator pinion, means including a toggle struc-

ture for meshing and unmeshing said pinion with said rack sector, said toggle being in straightened position for meshing the pinion with the rack sector, and a spring adapted to be brought into action at a predetermined position of the toggle for urging it toward and holding it in straightened position.

Signed at New York, in the county of New York, and State of New York, this 6th day of July, 1925.
